(57) **CLAIM**

The ornamental design for a display fixture with hanging sign, as shown and described.

DESCRIPTION

FIG. 1 is a top, front perspective view of a display fixture with hanging sign showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross sectional view taken along the line 8-8 in FIG. 1.

The broken line hatching in the cross sectional view forms no part of the claimed design.

1 Claim, 6 Drawing Sheets
